(57) **CLAIM**

The ornamental design for a container for storing pills, as shown and described.

DESCRIPTION

FIG. 1 is a top, right and front perspective view of the container for storing pills showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a bottom plan view of an alternate embodiment, with the surface containing concentric half circles;

FIG. 8 is a bottom plan view of another alternate embodiment; and,

FIG. 9 is a perspective view showing the container in an operating position for dispensing pills.
